UNITED STATES PATENT OFFICE.

MARTIN M. KENNEY, OF BRENHAM, TEXAS.

IMPROVEMENT IN FIRE-TONGS.

Specification forming part of Letters Patent No. **151,986**, dated June 16, 1874; application filed August 8, 1873.

To all whom it may concern:

Be it known that I, MARTIN M. KENNEY, of Brenham, in the county of Washington, State of Texas, have invented a new and useful Improvement in Fire-Tongs; and I hereby declare the following to be a full, clear, and exact description of the same, reference being had to the accompanying drawing forming part of this specification.

The invention consists in a fire-tongs, each leg of which is forked below the joint somewhat in the form of the letter **Y**. The diverging ends of the **Y**-shaped legs of the tongs are bent in the usual shape of the hips of tongs and riveted together, forming a joint of two separate rivets, so that a straight line passing through the axis of one rivet, and prolonged, passes also through the axis of the other.

The drawing represents a perspective view.

In the drawing, **P** and **P'** are the legs of the tongs, each forked below the joint. Both prongs of both the forked legs are bent in the usual shape of the hips of tongs, and united to form joints at **R** and **R'** by being formed into flat disks, (joint-bearings,) and riveted with rivets of suitable metal. The two joint ends of the leg **P'** are shouldered to fit over

the edges of the disks of the leg **P**. The latter are eccentric, being circular and concentric to the rivets in that part of their circumference over which the shoulders of the leg **P'** work in opening and closing the tongs, and tangent to the above-mentioned circle at the point reached by the shoulders of the leg **P'** when the tongs are open, the extent of the tongs being regulated by the shoulders of the leg **P'** coming against the eccentric circumference of the disks of leg **P**. Both prongs of the legs **P** are continued above the joints **R** and **R'**, and united at **S**, forming the handle of the tongs, so that, in fact, the leg **P** and handle **S** are one piece split, so as to form braces and joint-bearings for the forked end of the leg **P'**.

Having described my invention, what I claim as new, and desire to secure by Letters Patent, is—

The leg **P** and handle **S** formed in one piece, and split to form braces and joint-bearings for the forked end of the leg **P'**, substantially as described.

MARTIN M. KENNEY.
